WALLPAPER PASTING AND CUTTING
DEVICE

Odilon J. Boivin, Gorham, N. H.

Application May 29, 1947, Serial No. 751,205

1 Claim. (Cl. 91—14)

1 This invention relates to a device for pasting and trimming wallpaper.

A principal object of the invention is to provide a device of the type described, that will receive a roll of wallpaper, apply paste to one side thereof in the proper consistency, and trim one or both edges of the paper.

Other objects will appear to those skilled in the art from a reading of the following specification.

The accompanying drawings illustrate a preferred embodiment of the invention, but it is understood that modifications may be made therein without departing from the spirit of the invention as hereinafter claimed.

Figure 1 represents a plan view of the complete device, without wallpaper, ready for operation.

Figure 2 is a front elevation of the structure shown in Figure 1.

Figure 3 is a vertical section, on an enlarged scale, of a portion of the device, taken along the line 3—3 of Figure 1.

Figure 4 is a side elevation of the means for mounting the roll of wallpaper.

Figure 5 is a front elevation of a mechanism for wiping the wallpaper after paste has been applied thereto.

Figure 6 is a front elevation, similar to Figure 2, of a portion of the device in inoperative position.

Figure 7 is a front elevation of a platform for holding the wallpaper after it has been trimmed and pasted.

The device is usable on a table 10, which is supported on foldable horses 11. A wooden frame 12, open at the rear and at the top, is adapted to hold a paste pan 14. The pan 14 has a handle 16 to facilitate sliding of the pan 14 into and out of the frame 12. The pan 14 contains a saucer-shaped member 18 adapted to hold liquid paste and fastened at its upper periphery to the upper periphery of the pan 14. The transverse sides of the pan 14 are provided with slotted bearings to removably accommodate a pasting roll 20. Consequently, the pasting roll 20 can be easily removed from the pan 14 to be cleaned or for other purposes.

A roll of paper 21 is adapted to be held by two short horizontal holders 22 and 23. These holders 22 and 23 are carried on arms 24 and 26, respectively, which are pivoted on a horizontal shaft 27 mounted on the top of the front end of the frame 12. The pivoting of the arms 24 and 26 will take care of diminution in size of the roll of paper 21 as it is consumed. One of the arms 25

2 26 has a spring mounting 29 on the frame 12 to permit it to move resiliently along the shaft 27, for the purpose of accommodating varying widths of paper 21.

5 Pivotedly mounted on each side of the frame 12, by means of a hinge 31, is a bracket 32. When the bracket 32 is down in contact with the frame 12, as indicated in Figure 2 of the drawings, it is in the operative position. The bracket 32 may be locked to the frame 12 in the operative position by means of a catch 34 pivoted to the bracket 32, and a pin 36 fixed to the frame 12. When the bracket 32 is on end, in the position shown in Figure 6 of the drawings, the device 10 is in the inoperative position, and some of the parts may be removed for cleaning.

The two brackets 32 are journaled to receive the shaft 38 of a trimmer roll 40. The paper 21, the pasting roll 20, and the trimmer roll 40 will all be in parallel relation with one another. One end of the trimmer roll shaft 38 extends beyond the bracket 32 and is provided with a pulley 41 and a crank 42, for purposes to be described more fully hereinafter.

20 An angular arm 46, adapted to hold a rotary knife 50, is mounted on a pin 51 secured to the bracket 32 on each side of the frame 12, to cooperate with the trimmer roll 40 to trim one or both edges of the paper 21. Either one or 25 both arms 46 may be adjustable on their pivot pins 51 to vary the degree of trimming. In addition, each arm 46 has an adjustment 53 for controlling the pressure of the knife 50 against the trimmer roll 40.

30 It will be observed from Figure 3 of the drawings that the paper 21 is adapted to be passed over the top of the pasting roll 20, thence under the trimmer roll 40, and thence between the trimmer roll 40 and the knives 50. The arrows 35 in Figure 3 indicate the path of the paper 21.

To prevent the paper 21 from dipping into the paste after it leaves the pasting roll 20, a series of fingers 60, anchored at their rear ends to the bracket 32, project between the pasting roll 20 and the trimmer roll 40 so as to catch and guide the paper 21.

35 A wiper arm 62, pivoted to the sides of the bracket 32, is designed to bear against the paper 21 while it rotates with the trimmer roll 40 to wipe off excess paste. The wiper 62 has an angular extension 63, which is movable by means of an adjusting screw 64 to control the spacing between the wiper 62 and the paper 21, and consequently the thickness of the coat of paste to be borne by the paper 21. Two or more guide rollers

66 are mounted on resilient arms 67, which are secured to the upper pan member 18 and project between the fingers 60 to hold the paper 21 on the trimmer roll 40 so as to come into wiping contact with the wiper 62.

The front portion of each side of the bracket 32 is provided with an enlargement 70, to which are pivotally attached a series of lugs 71. A bar 72 is longitudinally slidably in each lug 71, and may be locked therein by means of a set-screw 73. The bars 72 constitute a grating for the purpose of supporting the pasted paper 21 after it leaves the trimmer roll 40. At the same time, the grating 72 will permit observation of the paper 21 as it unrolls from the holders 22 and 23. The grating 72 may have any desired shape, and is shown downwardly curved in Figures 2, 3, and 6 of the drawings.

One side of the frame 12 is provided with two pulleys 80 and 81, and the front end of the table 10 is also provided with a pulley 83. An endless rope 85 is snugly fitted over the pulleys 80, 81, and 83, and over the pulley 41 of the bracket 32. It will be obvious that as the top of the rope 85 is pulled toward the left, as viewed in Figures 1, 2, and 6, the pasted paper will travel as indicated by the arrows in Figure 3 and move off the grating 72 onto the top of the table 10, with the pasted surface of the paper 21 on top.

In the operation of the device, the upper pan member 18 is filled with paste. The brackets 32 and their associated elements are moved clockwise to the position shown in Figures 2 and 3, and locked by means of the catch 34. For further security, one or more barrel bolts 90 may secure the pan 14 to the frame 12 and to the table 10. A roll of paper 21 is positioned on the holders 22 and 23. The end of the paper 21 is then manually fed over the pasting roll 20, under the trimmer roll 38, and around and under the knives 50. This manipulation is facilitated by the crank 42 on the trimmer roll shaft 38. As the paper 21 travels across the pasting roll 20, it will of course receive a coating of paste from the rotating pasting roll 20. After the paper 21 has been properly started, it is only necessary to pull the rope 85 as hereinbefore mentioned, and the pasted paper can be withdrawn with one hand from the top of the grating 72. The paper 21 will have been properly wiped and trimmed, and will be ready for hanging.

Since the pasted side of the paper 21 will be uppermost, there will be no mess on the top of the table 10. The pasted paper can be cut transversely by any well known means.

What is claimed is:

A wall paper pasting and trimming machine comprising a hollow, rectangular frame, a past receptacle removably secured in said frame, a pasting roller journaled at its ends in said frame

in position to be partly submerged in paste contained in said receptacle, paper roll supporting means pivotally connected to the front end of said frame to support a paper roll contiguous and substantially parallel to said pasting roller at the front side of the latter, said supporting means being adjustable to receive rolls of paper of different widths, a bracket pivotally secured at its rear end to the rear end of said frame and movable between an operative position in which it rests upon the top edge of said frame and an inoperative position in which it extends upwardly from said frame substantially perpendicular to said top edge, said bracket having two spaced apart sides disposed one at each side of said frame, a trimming roller journaled in said bracket and disposed to the rear of said pasting roller and substantially parallel to the latter when said bracket is in its operative position, a trimming knife supporting arm mounted on said bracket, a trimming knife journaled on said arm and peripherally contacting said trimming roller, a plurality of spaced fingers secured to said bracket and underlying said trimming roller to guide the paper from said pasting roller onto said trimming roller, a plurality of spaced apart, curved bars pivotally connected to the front end of said bracket to overlie a paper roll supported on the front side of said frame and guide pasted paper from said trimming roller over to said paper roll, and manually operated means connected to said trimming roller for rotating the latter to move paper from said paper roll over said pasting roller and said trimming roller, said bracket being movable from its operative to its inoperative position to expose said paper roll support, said pasting roller and said trimming roller for replenishment of paper on said support, cleaning of said pasting roller and said trimming roller and for removal of said pasting roller and said paste receptacle from said frame.

ODILON J. BOIVIN.
